UNITED STATES PATENT OFFICE

CHARLES J. DUNBAR, OF KALAMAZOO, MICHIGAN, ASSIGNEE TO LE FEEURE CORPORATION, OF CEDAR RAPIDS, IOWA, A CORPORATION OF IOWA

LOOSE LEAF BINDER

Application filed June 8, 1929. Serial No. 369,307.

Loose leaf binders have been provided with clamping bars and detachable posts connecting the clamping bars in connection with fixed backs. Such a structure is exemplified in a patent heretofore granted to me, #1,709,843, dated Apr. 23, 1929. The present invention is designed to provide a binder which may be expanded to take in additional leaves and in which there are leaf-holding devices detachable from the binder which permit of an expansion as the binder is expanded.

A preferred embodiment of the invention is illustrated in the accompanying drawings 15 as follows:—

Fig. 1 shows a perspective view of a binder with one of the clamping bars detached and with the binder open and the parts detached.

Fig. 2 an enlarged view of a sheet-holding 20 cross bar.

Fig. 3 a section through the clamping bars and binding elements along the line 3—3 in Fig. 1.

Fig. 4 a perspective view of one of the binding posts.

Fig. 5 a similar view showing a post of greater length providing for expansion.

Fig. 6 a perspective view of the locking bar. 1 marks the clamping bars. These are 20 made of sheet metal of hollow box form. They are provided with sockets 2 for receiving the leaf-holding posts 3. Studs 4 are arranged on the inner face of the outer walls of the clamping bars and these extend into 35 sockets 5 in the ends of the posts. The posts have transverse locking slots 6 adjacent to their ends and locking bar 7 is provided with key-hole slots each having a narrow portion 9 the edges of which are adapted to enter the 40 slots 6 to lock the posts in place, and an enlarged opening 8 of sufficient size to receive one of the posts initially. The locking bar has a finger hold 10 at its end.

This locking means operates in the same 45 manner as the patent above referred to. When the locking bar is pressed inwardly bringing the openings 8 into register with the openings 2, the binding posts may be entered and then the locking bar is moved end- 50 wise bringing the edges of the narrow por-

tions 9 of the key-hole slots into the slots 6, thus locking the posts for use.

Sheets 11 are provided with the usual perforations 12 through which the posts extend. It will be understood that the clamping bars 55 are arranged at each side and that the posts are detachable from either of the clamping bars and that the locking bars on both sides are, or may be, identical.

A leaf-holding device is provided. As 60 shown, it comprises a cross-bar 13 with posts 14 extending into openings 14a in the leaves at one side of the binder, said bar having openings 15 through which the posts 3 extend. The post 14 may be extensible by providing the post with a screw-threaded socket 16 and sections 17 having screw-threaded extensions 18 may be secured on the post, each extension having in turn a screw-threaded socket 19 to which another section may be 65 added.

A similar bar 20 is arranged at the opposite side of the binder. It is provided with posts 21 which extend into openings 22 in the leaves. This bar 20 has openings 23 through 70 which the posts 3 extend. It will be noted that the posts 14 and 21 overlap and that this is conveniently accomplished by offsetting the posts, using separate holes for each post. This permits of an expansion 75 equal to the initial thickness of the leaf-holding device. It will be understood that the posts 21 have extending sections 17 similar to the extensions 17 on the posts 14.

In use the posts 3 may be detached from 80 the clamping bar at one side of the binder, the binder laid open, as shown in Fig. 1, the leaf body lifted through the engagement of the cross bars 13 and 20 and taken to the usual rack for use in the usual manner. An 85 extensible back 24 is secured to one of the clamping bars and extends into a pocket 25 in the cover of the opposite side of the binder.

It will be observed that for some uses but one of the cross-bars is used and in this event 90 the same extension of the posts of the cross-bar is useful for extension.

What I claim as new is:—

1. In a loose-leaf binder, the combination 95 of clamping bars; leaf-holding posts; means

for detachably securing said leaf-holding posts to the clamping bars to permit of post substitution for expansion; and a sheet-holding mechanism comprising a cross-bar at each side of the binder detachable with the leaf body from the binder, said bars having overlapping posts engaging the leaf body.

2. In a loose-leaf binder, the combination of clamping bars; leaf-holding posts; means for detachably securing said leaf holding posts to the clamping bars to permit of post substitution for expansion; and a sheet-holding mechanism comprising a cross-bar at each side of the binder detachable with the leaf body from the binder, said bars having overlapping posts engaging the leaf body, said cross-bars having openings through which the clamping posts extend.

3. In a loose leaf binder, the combination of clamping bars; leaf-holding posts; means for detachably securing said leaf-holding posts to the clamping bars to permit of post substitution for expansion; and a sheet-holding mechanism comprising a cross-bar at each side of the binder detachable with the leaf body from the binder, said bars having overlapping posts engaging the leaf body, said overlapping posts being extensible.

4. In a loose-leaf binder, the combination of clamping bars; leaf-holding post members; means securing said members to said clamping bars so as to be detachable from one of said clamping bars; and a sheet-holding mechanism comprising a cross-bar at each side of the binder detachable from the binder with the leaf body, said cross-bars having overlapping posts entering the leaf body.

5. In a loose-leaf binder, the combination of clamping bars; leaf-holding post members; means securing said members to said clamping bars so as to be detachable from one of said clamping bars; and a sheet-holding mechanism comprising a cross-bar at each side of the binder detachable from the binder with the leaf body, said cross-bars having overlapping posts entering the leaf body, said cross-bars having openings through which the clamping bar posts extend.

6. In a loose leaf binder, the combination of clamping bars; leaf-holding post members; means for detachably securing said post members to the clamping bars to permit of post substitutions for expansion; and a sheet-holding device comprising a cross-bar adapted to be placed between a clamping bar and a leaf body having post members thereon adapted to be extended to correspond with substitutions of post members on the clamping bars.

7. In a loose leaf binder, the combination of clamping bars; loose leaf post members; means detachably securing said post members to the clamping bars to permit of post substitution for expansion; and a sheet-hold-

ing device adapted to be impaled on said post members between a clamping bar and a leaf body and removable from the clamping bars with the included sheets, comprising an expanding post mechanism adapted to be extended to correspond with substitutions of post members on the clamping bars.

8. In a loose leaf binder, the combination of clamping bars; loose leaf post members; means for detachably securing said post members to the clamping bars to permit of post substitution for expansion; and a sheet-holding device adapted to be impaled on said post members between a clamping bar and a leaf body and removable from the clamping bars with the included sheets, comprising a cross-bar and expanding post mechanism thereon adapted to be extended to correspond with substitutions of post members on the clamping bars.

In testimony whereof I have hereunto set my hand.

CHARLES J. DUNBAR.
